AIR CONDITIONING APPARATUS

Norman H. Gay, Los Angeles, Calif.

Application December 2, 1935, Serial No. 52,577

9 Claims. (Cl. 62—139)

This invention relates to improvements in cooling and air conditioning systems, and is more particularly related to such a system wherein water and the evaporation of water are used as the principal or solitary agents for producing the cooling and conditioning desired.

A feature of the present invention is the cooling of the air below the initial wet bulb temperature of the air, with water used as the principal refrigerating agent.

Another feature is the provision of a simple arrangement for cooling and conditioning the ventilating air supply to a residence, store, building or other structure, with the employment of water as an agent for lowering the temperature thereof.

A further feature is the provision of means for utilizing water in producing a cooling and conditioning of ventilating air along with devices for automatically maintaining conditions of comfort in the space which it is desired to condition or ventilate.

With these and other features as objects in view, illustrative forms of practicing the present invention are shown diagrammatically in the accompanying drawings in which:

Fig. 1 is a view taken in vertical section showing an embodiment of the invention wherein the water velocity of the spray is used to introduce the movement of the conditioned air from the outside to the inside of the space to be conditioned.

Fig. 2 shows a similar view of an embodiment wherein a power driven fan is used to provide the necessary movement of air to be conditioned from the outside to the inside of the space to be conditioned.

Fig. 3 shows a similar view of a modified form in which water from an external source is used to effect the initial cooling of the air, and recirculated water is used for the final cooling of the air.

Fig. 4 shows a further modification, in which a mechanical refrigerating system is utilized to cool the air to a point below that at which it is possible to cool and condition the air with water alone.

Fig. 5 shows a further modification, in which evaporation cooling is employed directly at the radiator.

In each of these forms, a "radiator" (i. e., a device for exchange of heat between the air and the circulating liquid without direct contact therebetween) is utilized for the pre-cooling in order to avoid increasing the water content or relative humidity of the air being conditioned; and the final cooling is effected by spraying an

excess of water into the pre-cooled air, so that evaporation will cause a lowering of temperature of such excess and permitting its employment at such lower temperature during the course of its cycle.

In Fig. 1 is illustrated an apartment 10 whose atmosphere is to be conditioned according to the requirements thereof. Air is introduced to this apartment through duct 11, its motion being provided by the impinging effect of the particles of water from spray nozzle 12, which nozzle is working under pressure and throwing the water at relatively high velocity through the Venturi throat 13 in the diaphragm or partition 14 of the conditioning apparatus.

The air escapes from the apartment through the vent 15 which permits the air to pass to the outside and is preferably located at a point remote from the intake 17 so that the outgoing air will not mix with the fresh incoming air which is taken from the outside at 16 through an intake opening 17 at the entrance to the air conditioning apparatus.

The air passes through the filter 17a and through the radiator 18, which is kept at a temperature below that of the incoming air by means of a supply of cold water circulated as hereinafter described. In passing through the radiator 18 the air is pre-cooled to a lower dry bulb temperature and, since the dew point remains constant, to a new and lower wet bulb temperature. The air having been first cooled to this lower wet bulb, the water issuing from spray nozzle 12 further cools the pre-cooled air to a point near and above this new lower wet bulb and to a point below that at which it would have been possible to cool the air by spraying without pre-cooling with the radiator.

Water is taken from tank 19 in the bottom of the air conditioning apparatus through a conduit 20 and circulated by means of a pump 21 and a conduit 22 through the radiator 18 to give the radiator its cooling effect. The water then passes at higher temperature through a conduit 23 to a spray nozzle 12 for moving the air and at the same time cooling itself and the air circulated to a point near and above the wet bulb temperature of the pre-cooled air leaving the radiator. The air then passes on through a chamber 24 at a new and higher dew point and in a practically saturated condition. It passes through the eliminator 25, where any particles of unevaporated moisture are separated from it and returned to the tank 19, while the air itself passes on through the duct 11 to the apartment 10.

The air in apartment 10 is carried into the room downward in a practically vertical direction which throws it toward the floor, from which point it spreads out and rises at the walls to pick up the heat entering from the outside through the walls, then passes across the ceiling to pick up the heat passing downward through the ceiling, and finally leaves at vent 15, carrying with it the heat which it has picked up in the 10 room from the walls, ceiling, floor and other sources or containers of heat therein.

The water supply pipe 27 for the apparatus is connected with the city mains, a well, or any other available source of water supply. The supply to the apparatus is controlled by a float valve 28 operated by a float 29 in a manner to keep the water level in the tank 19 of the apparatus at the desired level.

It is obvious that the cooling of air is done by 20 means of the evaporation of water and that spraying the air also washes dust and other floating particles therefrom. Under normal conditions of water supply, the dissolved salts contained in such water supply and washings from 25 the air would be concentrated in the apparatus to a point where it would be no longer fit for use. To obviate and overcome this condition, overflow 30 is installed at a height which will permit a small portion of the water recirculated 30 to be constantly wasted from the supply contained in the tank 19 of the conditioning apparatus. In order to maintain temperatures which are not below those desired for apartment 10, when the capacity of the apparatus is greater 35 than the cooling effect desired, a thermostat 31 controls the supply of energy from a source 32, and operates to stop the pump 21 when the temperature in the apartment 10 reaches the desired low point, and to start the pump 21 when the 40 temperature in the apartment 10 reaches the desired high point.

Fig. 2 is a modification of Fig. 1, in which the apartment 10 to be conditioned is supplied with air through the duct 11. This air is here moved 45 by a fan 26. Air passes to the fan 26 through a duct 24a from the air conditioning apparatus. Air from the outside passes through the entrance opening 17, the dust filter 17b, and the radiator 18, where it is cooled in the same manner as described at Fig. 1.

The air leaving the radiator 18 at its new and lower wet bulb temperature passes through the sprays from spray nozzles 12a and 12b. Here the air is cooled to a temperature above and near 55 the new wet bulb temperature, and leaves the sprays in a practically saturated condition, passing onward through eliminator 25 and duct 24a to the fan 26.

Water from the tank 19 is circulated by the 60 pump 21 through the conduit 22 and radiator 18 to cool the air as above described, passing on at a higher temperature through conduits 23, 23a and 23b to spray nozzles 12a and 12b, where contact with the air cools it to a temperature 65 near and above the new wet bulb temperature of the air leaving radiator 18.

The air circulating in apartment 10 picks up the heat from the apartment and carries it out through the duct 15, as before described. The 70 temperature conditions in apartment 10 are maintained by the thermostat 31 as above described.

In Fig. 3, separate paths of circulation are employed for the water passing to the pre-cooling radiator and to the spray. Illustratively,

the spray is here employed as in Fig. 1, although obviously the fan of Fig. 2 may be incorporated. The air motion is caused by the impinging effect of the water particles passing through the Venturi throat, and the air path is the same as in Fig. 1. The water circulation is in two separate systems, one of which gives the air its initial cooling, and the other gives it its final cooling. Water for the initial cooling of the air is taken from cooling tower pan 45 through a conduit 46 to pump 21a which forces the water through conduit 22 and radiator 18, returning it through a conduit 47 to a cooling tower 48 where the heat acquired by the water at the radiator 18 is removed. Water for the final cooling is taken from the tank 19 through the conduit 20 by the pump 21 which forces it under pressure through the conduit 23 to the spray nozzle 12 where it gives the air its motion and final cooling and the excess falls back into tank 19.

In this form, a thermostat 31 controls the supply of power from the source 32 to the motor-pump assembly 21, and a separate thermostat 31a similarly controls the motor-pump assembly 21a; plural conductors being employed to indicate the possibility of employing a plurality of speeds at the pumps at differing positions of the thermostats. It is preferred, in this form, to control the two pumps separately, and according to the desired conditions of temperature and humidity. The thermostats may be set differentially with respect to one another, so that the pumps are selectively actuated according to the humidity and temperature conditions to be maintained.

Obviously the radiator water pre-cooling and final spray water cooling may be employed in conjunction with a further cooling by a refrigerating plant. Such an embodiment is shown in Fig. 4, indicating an illustrative development of Fig. 3, with mechanical refrigeration apparatus and controls therefor added. Water from the pump 21 passes through the conduit 23 to the evaporator 34, where it is cooled to a lower temperature and may be cooled to a temperature below the dew point of the outside air. It then passes onward through a conduit 33 to spray nozzle 12, where the impinging of the water creates the necessary air movement and at the same time chills the air and reduces it to the new desired temperature.

Air movement in the conditioning apparatus is the same as that described for Fig. 1. Water movement is the same as described for Fig. 3, except that the water used for the final cooling is diverted and its path carried through evaporator 34 to give it additional cooling.

The mechanical refrigerating equipment consists of a compressor 35, the evaporator 34 and the condenser 36. Gaseous refrigerant from the evaporator 34 is withdrawn through a conduit 31, compressed by the compressor 35, and introduced to the condenser 36 through a conduit 38. The refrigerant is condensed in the condenser 36 by means of any external source of water supply such as well, city mains, or cooling tower connected to the condenser water inlet 39; such water being circulated through the condenser and leaving at the water outlet 40 to pass to sewer drain or to return to cooling tower. The liquefied refrigerant from the condenser 36 passes to the receiver 41 and thence through a conduit 47 and an expansion valve 43, and into the evaporator 34.

A control of the temperature in the apartment 10 is accomplished by means of a thermostat 31b controlling energy from a source 32 and serving

to stop the compressor 35 when the temperature of the apartment 10 reaches the desired low point and to start and control the compressor 35 when the temperature of the apartment 10 reaches the desired high points. Thermostats 31 and 31a similarly operate to start and stop pumps 21 and 21a when additional temperature regulation is required.

In Fig. 5 is shown a further modification of the arrangement. The air for the apartment is introduced from the exterior at 16 through the opening 17, past the filter 17b and between the fin surfaces of a tube-and-fin radiator 18x, and then is contacted with water from the spray nozzle 12 and thus moved through the venturi 13 into the chamber 24, passing through the eliminator 25 and the duct 11 into the apartment 10, from which it escapes through the vent 15 as before. Water is moved to the nozzle 12 by the pump 21, through conduit 23. Excess of water is then collected in the sump 19 as before, and passes back to the pump 21 by conduit 20. The water level in sump 19 is maintained from the supply pipe 27 by the valve 28 under control of the float 29. An overflow 30 is provided for continuously discharging water from the sump 19 as stated above.

In this form of the structure, an auxiliary air inlet 17x is provided, through which air is moved by water projected from the nozzle 12x into venturi 13x, from which it moves through the tubes of the radiator 18x in a downward direction. An excess of water is always preferred, so that the inner walls of these tubes are traversed by a film 35 of water cooled by the air, and by the evaporation from the surfaces thereof, so that a rapid heat transfer occurs in the radiator, without contact of the water with the air. The saturated air from the tubes then passes through an eliminator 25x and is exhausted by duct 11x. The excess water drips from the lower ends of the radiator tubes into a sump 19x, and is withdrawn therefrom by a conduit 20x to the pump 21a, and thus forced through conduit 23x to the nozzle 12x. 40 The water level of sump 19x is maintained by a branch supply pipe 27x under control of the valve 28x as actuated by float 29x. An overflow 30x is provided to avoid accumulation of dirt and soluble salts in the sump and water circulation of 45 this portion of the system.

In this form, the two pumps 21 and 21a are illustrated as operated by a common motor 21m which further is illustrated as controlled by a thermostat 31 and energized from a source 32.

It will be noted that, in each of the embodiments of the invention above described, the air to be conditioned passes first through a surface type of radiator, wherein the air is cooled without coming in direct contact with the water, and 55 then passes to and through a spray or system of sprays wherein it is further cooled and humidified. The advantage of this type of apparatus is that, by first cooling the air without bringing it in contact with the water, the dew point of 60 the air remains constant and the dry bulb temperature is brought to a considerably lower point with a consequent reduction of the wet bulb temperature of the air. It is well known that the wet bulb temperature of the air is the indicator 65 of the point to which air can be cooled by spraying it with water, and hence by creating a new wet bulb for the air to be conditioned, the air is placed in condition for cooling to a lower final temperature. Greater advantage is thus taken 70 of the ability of the air to replace the sensible

heat of the air with the latent heat of the water, for example, with air at 105° F. dry bulb temperature and a dew point of 50° F., the wet bulb temperature existing is approximately 70° F., with a relative humidity of 16%. A single spraying 5 of the air with water cannot reduce the temperature of the air below this established wet bulb of 70° F. On the other hand, it is possible to cool the air to nearly 70° F. if the proper volume of water at, say, 80° F. is used for spraying, since both the air and the water are cooled to a temperature near and just above the initial wet bulb temperature of the air (70° F.). If 10 the air be cooled, however, with a radiator instead of a spray, to a new dry bulb temperature 15 of 75° F., with the dew point remaining constant, the new wet bulb temperature existing when the air leaves the radiator will be 60° F. The rise in temperature of the water in the radiator can be pre-determined if the volume of the 20 air circulated is known and sufficient volume circulated to give a rise of say 5°. In the embodiment shown in Fig. 1, a spraying of air (at 60° F. wet bulb temperature) with this water, which will have a temperature of approximately 25 69° will permit reducing the air temperature, so that the air leaves the sprays at a temperature of approximately 64°, while the water also 30 will be reduced to a temperature of approximately 64° F. In the embodiment shown in Fig. 3, the heat acquired by the water at radiator 18 is entirely removed and disposed of at the cooling tower 48. The water delivered to spray nozzles 12, 12a, 12b is at the same temperature as the water leaving the air and falling 35 into the tank 19. This temperature is very close to the wet bulb temperature of the air (say 61°). Air leaving the spray is practically saturated with moisture and is at the same temperature as the water (or 61° also), so that in 40 the example given, the dual water circulation shown in Fig. 3 cools the air to a 3° lower wet bulb temperature.

In the above examples it is assumed that volumes of air, volumes of water, area of surface, 45 and amount of spray, are properly proportioned to give the temperatures illustrated in the example.

This system of air conditioning makes it possible, by using water alone as a refrigerant, to 50 bring the air to a lower temperature before it is necessary to utilize mechanical refrigeration, than is afforded with ordinary systems which employ sprays for air conditioning. It is apparent that the volume of water evaporated will be relatively small, and the water economy is limited 55 only by the necessity for freshening the water due to concentration of soluble salts originally contained in the water supply. It is obvious that changes might be made to accord with the necessities of conditions and structures, without departing from the scope of the appended claims, 60 and that the illustrative forms are not restrictive in the practice of the invention.

I claim:

1. In an air conditioning system, means providing a path for the movement of air, a radiator positioned in said path, Venturi throat equipment in said path downstream of said radiator and through which all air must pass, means supplying a cooling medium to the radiator and directing cooling liquid spray into said throat equipment to provide successive treatments for the air, said spray and throat equipment constituting the sole means for conveying air through

- said path and means for individually controlling the supplying of cooling medium to the radiator and to the spray whereby the cooperative effect of said radiator and spray can be varied.
5. 2. In an air conditioning system, means providing a path for the movement of air, a radiator positioned in said path, Venturi throat equipment in said path downstream of said radiator and through which all air must pass, means supplying a cooling medium to the radiator and directing cooling liquid spray into said throat equipment to provide successive treatments for the air, said spray and throat equipment constituting the sole means for conveying air through said path, and means for automatically exercising individual controls over the operation of said radiator and spray in response to conditions in the area being air conditioned for varying the cooperative effect of said radiator and spray to the extent of at times causing one thereof to function to the exclusion of the other.
3. In an air conditioning system, means providing a path for the movement of air, a radiator positioned in said path, a Venturi throat equipment in said path downstream of said radiator and through which all air must pass, separate means for supplying a cooling medium to the radiator and for directing cooling liquid spray into said throat equipment to provide successive treatments for the air, said spray and throat equipment constituting the sole means for conveying air through said path, said separate means each including a circulating pump, and means responsive to conditions in the area to be air conditioned for automatically controlling the operation of said pumps.
4. In an air conditioning system, means providing a path for the movement of air, a radiator positioned in said path, a Venturi throat equipment in said path downstream of said radiator and through which all air must pass, separate means for supplying a cooling medium to the radiator and for directing cooling liquid spray into said throat equipment to provide successive treatments for the air, said spray and throat equipment constituting the sole means for conveying air through said path, said separate means each including a circulating pump, and means responsive to conditions in the area to be air conditioned for individually controlling the operation of the pumps whereby the cooperative effect of the radiator and spray can be varied.
5. In an air conditioning system, means providing a path for the movement of air to be conditioned, a radiator positioned in said path, Venturi throat equipment in said path downstream of said radiator and through which all air to be conditioned must pass, said radiator including tubes traversing the air path, and means for projecting cooling liquid spray into the tubes to bathe the interior walls thereof with a film of cooling liquid and for directing cooling liquid spray into said throat equipment to provide for two step cooling of the air, said spray and throat equipment constituting the sole means for moving the air through said path.
6. In an air conditioning system, means providing a path for the movement of air to be conditioned, a radiator positioned in said path, Venturi throat equipment in said path downstream of said radiator and through which all air to be conditioned must pass, said radiator including tubes traversing the air path, means including a Venturi throat and a cooling liquid spray directed through said throat into the tubes to bathe the interior walls thereof with a film of cooling liquid and induce a current of air through said tubes, and means for directing cooling liquid spray into said throat equipment to cause movement of air to be conditioned through said path and provide for a second step cooling of the air succeeding the cooling thereof by the radiator.
7. In an air conditioning system, means providing a path for the movement of air to be conditioned, a radiator positioned in said path, Venturi throat equipment in said path downstream of said radiator and through which all air to be conditioned must pass, said radiator including tubes traversing the air path, means including a Venturi throat and a cooling liquid spray directed through said throat into the tubes to bathe the interior walls thereof with a film of cooling liquid and induce a current of air through said tubes, and means for directing cooling liquid spray into said throat equipment to cause movement of air to be conditioned through said path and provide for a second step cooling of the air succeeding the cooling thereof by the radiator.
8. In an air conditioning system, means providing a path for the movement of air to be conditioned, a radiator including tubes traversing the air path, and a Venturi throat and cooling liquid spray unit disposed adjacent the radiator and serving to project a spray through the throat into the tubes to bathe the interior walls of the tubes with the cooling liquid and constituting the sole means for inducing a current of air through said tubes.
9. An air conditioning system comprising means providing a path for the movement of the air to be conditioned, a radiator exposed to the air moving along said path, means providing a Venturi throat in the path downstream of the radiator, a spray device located at said throat for delivering water into the air to effect movement thereof, a water eliminator located downstreamward of the spray device, means for moving cooling liquid to the radiator for effecting an initial precooling of air thereat without direct contact with the liquid, a reservoir for water, means for supplying to and constantly overflowing from said reservoir a regulated amount of water whereby to remove with the overflowing water impurities separated from the air by the water spray, and means for delivering water from the reservoir to the spray device at a rate in excess of the capacity of the air to evaporate and receive the same and effecting a secondary cooling by direct contact of the air and the water of the spray, said eliminator operating to remove the excess of water before the conditioned air leaves said provided path.

NORMAN H. GAY.
